UNITED STATES PATENT OFFICE.

JOHN A. BREWER, OF JACKSON, MICHIGAN, ASSIGNOR TO ELECTRIC SHOE POLISHER COMPANY, OF JERSEY CITY, NEW JERSEY, A CORPORATION OF NEW JERSEY.

SHOE-POLISHING MACHINE.

No. 863,352.

Specification of Letters Patent.

Patented Aug. 13, 1907.

Application filed August 1, 1906. Serial No. 328,783

To all whom it may concern:

Be it known that I, JOHN A. BREWER, a citizen of the United States, residing at Jackson, in the county of Jackson and State of Michigan, have invented new and 5 useful Improvements in Shoe-Polishing Machines, of which the following is a specification.

This invention relates to that class of shoe polishing machines in which the operating mechanism is set in motion by the dropping of a coin and it has for its object 10 to simplify and improve the construction and operation of this class of machines.

With this and other ends in view which will readily appear as the nature of the invention is better understood, the same consists in the improved construction 15 and novel arrangement and combination of parts which will be hereinafter fully described and particularly pointed out in the claims.

In the accompanying drawings is illustrated a simple and preferred form of the invention; it being however, 20 understood that no limitation is necessarily made to the precise structural details therein exhibited, but that changes, alterations and modifications within the scope of the invention may be resorted to when desired.

In the drawings: Figure 1 is a front elevation, partly 25 in section, of a machine embodying the invention. Fig. 2 is a vertical sectional view of the upper portion of the machine. Fig. 3 is a vertical transverse sectional view taken on the plane indicated by the line 3—3 in Fig. 2. Fig. 4 is a diagram illustrating the movement 30 of the belt whereby the shoe polishing devices are operated. Fig. 5 is a diagram illustrating the electrical circuit including the motor whereby the machine is operated.

Corresponding parts in the several figures are denoted 35 by like characters of reference.

A suitable casing is provided having a bottom compartment 1 and an upper compartment 2. A tubular standard 4 rising from the casing is in communication with the bottom compartment of the latter, and said 40 standard supports at its upper end an auxiliary casing 5; the latter being connected with the tubular standard 4 by means of braces 6 which constitute handles adapted to be grasped by the person using the machine who may thus support himself in a convenient position.

45 The partition 7 which separates the bottom compartment 1 from the upper compartment 2 is provided with bearings for shafts 8, 9 one of which carries a brush 10 and the other a buffer or polisher 11 which latter may be composed of pieces of felt or textile material so arranged 50 that their edges shall constitute the working face of the polisher. The latter as well as the brush is preferably of an inverted conical or frustum shape illustrated in the

drawings, although they are not necessarily limited to this shape. The shafts 8 and 9 are provided near their lower ends with grooved pulleys 12 and 13 for the passage 55 of the belt 14 whereby they are driven. Within the compartment 1 of the casing is mounted an electric motor 15 the shaft of which 16 carries a grooved pulley 17; the belt 14 is guided over the pulleys 12, 13, 17 and over a pair of guide pulleys 18, 19 which are suitably 60 supported below the partition 7 so that, when the motor is in operation, rotary motion will be transmitted to the brush and the polisher.

The shaft 16 of the motor has a worm 20 meshing with a worm gear 21 upon the lower end of the shaft 65 22 which latter extends vertically through the tubular standard 4 into the auxiliary casing 5; the latter is provided with bearings for a horizontally disposed shaft 23 which projects at one end through the casing and carries a hand or pointer 24 that moves over a 70 dial 25; the shafts 22 and 23 are provided with intermeshing bevel gear 26, 27.

The auxiliary casing 5 is provided with a coin chute 28 terminating adjacent to a pair of plates 29 which are suitably spaced apart, said plates being constructed 75 of glass or similar non-conducting material. Adjacent to the plates 29 are binding posts 30, 31 with which are connected springs 32, 33 that extend between the plates 29 in the direction of each other so that said springs together with the plates 29 will constitute an extension or continuation of the coin chute. The spring 32 is extended below the plates 29 as will be clearly seen at 34 in Figs. 2 and 3 of the drawings. Connected with the binding post 31 is an additional spring 35 which is inclined downward adjacent to one of the plates 29; 80 85 said spring being extended beyond the extension 34 of the spring 32. The springs 32, 33 and 35 constitute electrical conductors; and a shaft 22 is provided with a radial arm 36 adjacent to the lower edges of the plates 29 said arm being adapted to engage the lower end of 90 the spring 35 and the extended end 34 of the spring 32.

The binding post 30 is connected by a conductor 37 with one pole of the motor 15; the other pole of said motor being connected with the source of power by a conductor 38. A conductor 39 connects the source of 95 power with the binding post 31 as will be best seen by reference to the diagram in Fig. 5 of the drawings.

When the coin is dropped through the chute 28 it will be caught between the springs 32, 33, and will thus complete an electrical circuit whereby the motor 100 15 will be set in motion. The user of the machine, steadyng himself by the handles, applies his feet in succession to the brush 10 and the polisher 11. The motor serves to rotate the shaft 22 the arm 36 of which

will presently pass into engagement with the projecting end 34 of the spring 32 which latter will thus release the coin and permit the latter to drop; the circuit will however remain unbroken until the arm 36 passes 5 out of engagement with the spring 35 which projects beyond the extended end of the spring 32, so that the latter will be released from the arm 36 before the motion ceases; said spring 32 will thus be restored to normal position for engagement with the next coin that 10 may be introduced into the box.

It will be seen that the shaft 22 will make a complete revolution for every coin introduced into the device; and the pointer 24 is intended to make a complete circuit of the dial 25 simultaneously therewith, 15 thus enabling the user of the machine to properly gage the amount of work bestowed upon each shoe.

The improved device is simple in construction, and it has proven to be thoroughly efficient in practical operation.

Having thus described the invention what is claimed 20 is:

A shoe polishing machine comprising a casing having a horizontal partition therein, an upright standard secured to said casing, an auxiliary casing at the top of said standard, shafts journaled in said partition, frusto-conical 25 polishing and cleaning brushes secured to said shafts, a motor in said casing, a worm on the motor shaft, a vertical shaft extending through said standard and operatively connected with the worm on the motor shaft, a pulley on the motor shaft, a pulley on each of the brush shafts, pulleys 30 supported under the partition, a belt passing around said pulleys, means for starting said motor and rotating said brushes, and means on said vertical shaft for automatically stopping the rotation of said brushes, after a predetermined lapse of time.

In testimony whereof, I affix my signature in presence 35 of two witnesses.

JOHN A. BREWER.
